UNITED STATES PATENT OFFICE

EBICH ASCHE, OF SUDENDE, NEAR BERLIN, GERMANY, ASSIGNOR TO RADIO PATENTS CORPORATION, OF NEW YORK, N. Y., A CORPORATION OF NEW YORK

CONTINUOUS CURRENT AMPLIFIER

Application filed January 3, 1930, Serial No. 418,311, and in Germany January 8, 1929.

This invention relates to an improved continuous current amplifier in which amplification is obtained by connecting the anode of the one stage direct to the grid of the subsequent stage without using an intermediate alternating current repeater.

In my specification No. 314,768 I have described a continuous current thermionic amplifier in which such very large loading resistances are inserted in the anode circuits between the anodes and the positive pole of the source of high tension current that the effective cathode drop is only a small fraction of the available drop. In that specification I have also described the combination of the anode of one stage with the grid of the next stage in one electrode and also the use of such an electrode as a carrier for the cathode which is insulated therefrom.

If the continuous current amplifier described in the specification referred to is operated from an alternating current supply and if it is desired to keep the consumption as low as possible, the source of current for the anodes may be separated from the sources of current heating the filaments.

In the accompanying drawing E is a continuous current voltage which may for instance be obtained by the rectification of an alternating current voltage and from which only the emission current of the last tube need be derived, since the emission of the preliminary tubes is practically nil. The heating of the tubes may be effected by separate batteries, or as shown in the drawing, by means of alternating current. In the drawing the last tube is heated directly and the preliminary tube indirectly by means of alternating current. The necessary drop between the cathodes may be produced by a resistance inserted between the cathodes and over which flows the emission of the subsequent tubes.

In the drawing α is the input of a two-stage amplifier, β the output, I_1 and I_2 are the two tubes, w is the coupling resistance and r the resistance in which the emission of the tube I_2 produces a drop of about 20-30 volts between the two cathodes. In order exactly to regulate the grid bias of the second

tube, the resistance r may be made wholly or partly adjustable.

Of course the amplifier when used only for relay or measuring purposes may be fed by an alternating current source instead of a continuous current. The amplifier also may be increased beyond two stages and the assembling of the electrodes in the manner described in specification No. 314,768 may also be adopted in the present invention.

What I claim is:—

1. In a direct coupled electron tube cascade system comprising at least a first discharge tube, a second discharge tube, said tubes having filament, anode and control electrodes, a direct coupling connection from said first tube to the control electrode of said second tube, a source of operating current, said tubes being connected across said source in parallel, series resistors in the supply leads of said tubes for producing proper biasing potential of said second tube and means for maintaining the filament potential independent of the filament heating current.

2. An electron tube cascade system as described in claim 1, in which tubes with indirectly heated cathodes are provided.

3. An electron tube cascade system as described in claim 1, which uses tubes with direct heated filaments with a separate heating transformer for each filament.

4. In a direct coupled electron tube cascade system comprising at least a first thermionic tube, a second thermionic tube, said tubes having filament, grid and plate electrodes, a direct coupling connection from the plate of said first tube to the grid of said second tube, a source of operating voltage for said tubes, each of said tubes being supplied from said source in parallel, and means for maintaining the potential of the filaments of the tubes independent of the filament heating current.

5. A vacuum tube cascade system as described in claim 4 in which tubes with indirectly heated cathodes are provided.

6. A cascade system as described in claim 4, which uses tubes with direct heated filaments with a separate heating transformer for each filament.

7. In a direct coupled electron tube cascade system comprising a first discharge tube; a second discharge tube, said tubes having cathode, anode and control electrodes; a direct coupling connection from said first tube to the control electrode of said second tube; a source of operating current; an impedance connected in the anode circuit of said first tube; an impedance connected in the cathode circuit of said second tube; circuit connections including said impedances for connecting said tubes in parallel across said source of operating current; and means for indirectly heating the cathode of said first tube.
8. In a direct coupled electron tube cascade system comprising a first discharge tube; a second discharge tube, said tubes having cathode, anode and control electrodes; a direct coupling connection from said first tube to the control electrode of said second tube; a source of operating current; a resistance connected in the anode circuit of said first tube, a resistance connected in the cathode circuit of said second tube; circuit connections including said resistances for connecting said tubes in parallel across said source of operating current; and means for indirectly heating the cathode of said first tube.

30. In testimony whereof I affix my signature.
Dr. ING. ERICH ASCH.
